(57) **CLAIM**

(**) Term: **14 Years**

The ornamental design for a base terminal for lighting control, as shown and described.

(21) Appl. No.: **29/237,796**

DESCRIPTION

(22) Filed: **Sep. 7, 2005**

FIG. 1 is a top, front and right side perspective view of a base terminal for lighting control, showing our new invention;

(30) **Foreign Application Priority Data**

FIG. 2 is a bottom, front and right side perspective view thereof;

Mar. 7, 2005 (JP) 2005-006629

FIG. 3 is a front elevation view thereof;

(51) **LOC (8) Cl.** **13-03**

FIG. 4 is a rear elevation view thereof;

(52) **U.S. Cl.** **D13/147; D13/159**

FIG. 5 is a top plan view thereof;

(58) **Field of Classification Search** D13/133,

FIG. 6 is a bottom plan view thereof;

D13/146, 147, 154, 159, 164, 184, 199; 439/151–153,
439/246, 249, 283, 374–375, 540.1, 541.5,
439/660, 668

FIG. 7 is a left side elevation view thereof;

See application file for complete search history.

FIG. 8 is a right side elevation view thereof;

(56) **References Cited**

FIG. 9 is a sectional view thereof, taken along line “9—9” in FIG. 6, and,

U.S. PATENT DOCUMENTS

FIG. 10 is a top, front and right side perspective view thereof, in use condition.
